GLIDER HANGER

Filed Feb. 12, 1949

UNITED STATES PATENT OFFICE

2,634,793

GLIDER HANGER

John S. Petersen, Kenosha, Wis., assignor to Simmons Company, Kenosha, Wis., a corporation of Delaware

Application February 12, 1949, Serial No. 76,026

1 Claim. (Cl. 155—58)

1

The main objects of this invention are to provide an improved form of hanger for swingably suspending a glider seat and back frame from a supporting frame; to provide an improved form of tubular member suitable for use as a glider hanger of this kind; to provide an improved manner of mounting on the lower end of such a tubular member a bearing for support of the glider seat and back frame; and to provide an improved formation of the upper end of such tubular member for connection to a ball bearing secured to the glider-supporting frame.

In the accompanying drawings:

Fig. 1 is a perspective view of a glider chair wherein the seat and back frame are suspended from a supporting frame by two pairs of hangers embodying this invention;

Fig. 2 is an enlarged side elevation of a hanger embodying this invention, showing the manner of its attachment to both the seat and back frame and to the supporting frame;

Fig. 3 is a front elevation, partly sectional, of the hanger shown in Fig. 2, the view being taken on the plane of the line 3—3 of said Fig. 2; and

Fig. 4 is an enlarged detail view of a ball bearing member of the type suitable for anchoring to the glider supporting frame, to which ball bearing is attached the upper end of a hanger embodying this invention.

A glider wherein this improved form of hanger is adapted for use comprises, a supporting frame 4 whereon is swingably suspended a seat and back frame 5 by four of the preferred type of hangers 6 embodying this invention. The glider herein shown is in the form of a chair, all of the framework of which is of tubular construction.

The supporting frame 4 includes two end members, each of which is approximately sector-shaped. The part 7 is adapted to rest on the floor with the right-angularly-disposed part 8 extending upwardly, whereby the upper portion of the arcuate-shaped part 9 provides for the attachment of ball bearings 10 wherefrom the hangers 6 suspend the seat and back frame 5. These two end members are connected by transverse braces 11, two of which extend between the floor parts 7 and one each between the upright parts 8 and the arcuate parts 9.

The seat and back frame 5 is bent to form the usual angularly-disposed portions 12 and 13 whereon is stretched a suitable metal fabric 14 for the support of the usual upholstered seat and back cushions 15 and 16.

In its preferred form, the hanger comprises a tubular member 6 having a vertical upper portion and a lower portion 17 which is bent or curved so that the axis of the tube at its lower end is disposed at an angle to the longitudinal axis of the main or straight portion of the tube. Preferably, the open, lower tube end is parallel to the axis of the straight portion, and the angle

2

of the bend is less than ninety degrees in order to reduce the spacing between the open end of the tube and the axis of the vertical portion. A seat and back frame supporting shaft or pin 18 has a frusto-conical hub 19 integrally-formed thereon which is telescopically seated in the open end of the extremity 17 with the axis of the shaft 18 extending substantially perpendicularly to the straight portion of the member 6.

The hub 19 is welded into the lower end of the tubular member 6 or otherwise bonded in placed with the base thereof flush with the perimeter of the open end of the extremity 17. For connecting the seat frame 5 with each of the hangers 6, the seat frame is preferably provided with bushings 20 which are secured in suitable openings in the side members of the seat frame, and which receive the pins or shafts 18. The usual washer 21 and cotter pin 22 are arranged on the end of the pin 18 to maintain the connection thereof to the seat frame 5.

The upper extremity 23 of the hanger 6 is flattened and bifurcated to provide a pair of ears 24 whereon is supported a pin 25 which is adapted to extend through and be supported on a ring 26 of a ball bearing element 10. The outer ring 27 of the ball bearing 26 is formed with a lug 28 whereby the ball bearing 10 is suspended from the under side of the upper portion of the arcuate part 9 of the tubular supporting frame 4.

Variations and modifications in the details of structure and arrangement of the parts may be resorted to within the spirit and coverage of the appended claim.

I claim:

A glider hanger in the form of a generally vertically extending metallic tubular member having a straight upper portion and a lower portion which is curved to dispose the axis of the lower end of said member at an angle to the axis of said straight portion, the upper end of said member being bifurcated to form a pair of spaced ears, a pin extending through and between said ears, a bearing surrounding said pin for suspending said hanger from a supporting frame, and a bearing shaft seated and secured in said lower tube end and extending outwardly therefrom on an axis perpendicular to the axis of the straight portion of said member.
